CONTROL APPARATUS FOR ELECTRIC SIGNS

Filed Dec. 12, 1929

UNITED STATES PATENT OFFICE

FRANCIS E. J. WILDE, OF FOREST HILLS, NEW YORK

CONTROL APPARATUS FOR ELECTRIC SIGNS

Application filed December 12, 1929. Serial No. 418,477.

The present invention relates to apparatus for the operation and control of electric signs, particularly the so-called "talking signs" wherein lights mounted in a bank on a suitable board are selectively flashed to produce the effect of traveling characters as, for instance, letters or symbols of any kind. The invention specifically contemplates certain improvements and refinements of operation in apparatus of the type shown and described in my prior Patents 1,626,899 and 1,626,900, and in my copending application Serial No. 312,015, filed June 29th, 1929.

In apparatus of the general class referred to herein, these traveling sign effects are usually produced by passing patterns of the desired characters or outlines in proper succession past a bank of contact devices which are actuated by the patterns and thereby operate to energize correspondingly located lights on the sign board, with the result that the travel of the character patterns past the contact bank produces a corresponding travel of illuminated characters across the sign board. The best operation of such signs requires that a continuous passage or circulation of character patterns, properly spaced and in proper sequence be maintained past the contact bank. The character patterns or sign plates commonly consist of a block or backing provided at its front face with a raised character, as for instance, a single letter, number, or the like. Handling of these individual sign plates in rapid succession past the contact bank and in returning them in proper order and relation for repetition of the sign without incurring irregularities in operation which disturb or interrupt the presentation of the sign is a matter of some importance in apparatus of this class.

It is a principal object of this invention to provide, in apparatus of the class referred to, an improved means of handling the individual character patterns or sign plates, and the invention has to do particularly with means for positively controlling and handling the sign plates throughout the entire cycle of operation so that proper spacing and sequence of the sign plates past the contact

bank is assured, and so that danger of jamming and stoppage of the sign plates at all points in their passage from the discharge side of the contact bank back to the intake side of the contact bank for repetition is definitely eliminated.

It is also an object of the invention to provide means for handling the sign plates out of the contact bank and reversing and arranging them in proper position for repetition of the sign which effects an expeditious, positive and accurate handling of the plates with a minimum space requirement.

It is a still further object to provide various improvements in construction and design of apparatus of this general class, and particularly to provide an improved mechanical and electrical construction for certain details of the contact bank.

The novel features of construction, combination and relation of parts by which the foregoing and other desirable objects are attained are set forth below and illustrated in the accompanying drawing which shows certain preferred embodiments of the invention.

In said drawing Figure 1 is a side elevational view, largely in section, of a preferred form of apparatus embodying the invention and designed for minimum space requirements; Figure 2 is a side elevational view of a slightly modified form of apparatus of somewhat different relative proportions; Figure 3 is an enlarged sectional detail view of a portion of the apparatus of Figure 1, the view being taken on the plane indicated at 3-3 in Figure 1; and Figure 4 is a sectional view showing a detail of the contact bank.

Referring particularly to Figures 1 and 2 of the drawing, 1 indicates the storage reservoir or magazine for the character patterns or sign plates with the sign plates 2 stacked therein in super-imposed relation. Each of the sign plates 2 consists, as better shown in Figure 3, of a base member or backing 3 of insulating material having provided thereon a character pattern 4 made of relatively thin material which is a good electrical conductor, as for instance, brass. The character pattern on each sign plate consists of a single letter

100

or other symbol. The insulating backing 3 of the sign plate carries lugs or runners 5 on its front face, which lugs extend out beyond the face of the character symbol 4 which is carried by the base plate so that, when the sign plates are stacked in the magazine 1, the character patterns 4 are saved from contact with the adjacent plates. This construction also facilitates removal of the sign plates at the bottom of the magazine inasmuch as it reduces the friction between the plates and enables the bottom plate of the stack to be slid out without application of undue force. The exact construction and design of the sign plates 2 is not a part of this invention, and it is therefore understood that any suitable type of sign plate may be employed, as for instance the particular kinds of sign plates disclosed in my above-mentioned patents and copending application.

In the apparatus here shown, the sign plates 2 feed downwardly through the magazine 1 under the influence of gravity but, if desired, a positive feed, such as disclosed in my above-mentioned copending application, may be used. The sign plates 2 are removed from the bottom of magazine 1, one at a time, the sign plates being deposited on and carried by chains 6. These chains carry the sign plates in closely spaced relation upwardly past the contact bank 7. The sign plates 2 lie face downwardly in the magazine so that, when they are deposited on chains 6, the electrically conducting character pattern on each plate faces downwardly and is thus carried around in such position that the character patterns properly face the contact bank. The contact bank 7 consists essentially of a series of fixed contact posts 8 each provided with a fixed wire or connection, not shown, which leads to a lamp on the sign board and serves to actuate same. Cooperating with fixed contact posts 8 are a corresponding number of contact brushes 9 which are in the form of narrow flexible strips of bronze or other good conducting metal. These contact brushes 9 pass over the face of the sign plates 2 as the sign plates move past the contact bank. Those of the brushes 9 which come in contact with the electrical conducting character pattern thereby complete the energizing circuit for the lamp in the sign board to which that particular contact brush is connected. The result is that lights on the sign board are selectively lighted or flashed in the form of characters corresponding to the character patterns on the sign plates.

The entire contact bank is mounted in a frame 10 pivoted at its bottom edge 11 and removably secured at its upper end as indicated at 12 so that the entire contact bank can be swung out at a moments notice to facilitate replacement of worn contacts. A contact bank of this general type is shown

and described in detail in my above-mentioned copending application.

The sign plate carrying chains 6 consist of two chains in parallel arrangement spaced apart, as shown in Figure 3, such distance as is appropriate for carrying the sign plates 2. Each of the chains 6 is an endless chain operating over an end sprocket 13 at the bottom terminal portion of the chain, a sprocket 14 which turns the chain from a downward vertical direction into a horizontal direction, and sprockets 15 at the upper end of the apparatus which serve to support and carry the chain around the sign plate reversal portion of the apparatus. The sprockets 80 are built in pairs for the respective chains, each pair of sprockets being connected by a shaft fixed to the sprockets to assure synchronous operation of the two chains. The driving power of the apparatus is furnished by motor 16 driving the shaft 17 of sprockets 14 through driving connections indicated diagrammatically at 18 but not shown in detail. In the embodiment shown the direction of rotation of all of the sprockets is counter-clockwise so that the inner flights of the chains 6 which carry the sign plates 2 operate upwardly past the contact bank 7, around the reversing bend at the top of the apparatus and back downwardly to the bottom of the apparatus around sprocket 13 to the magazine.

Each of the chains 6 carries a series of lugs 19 positioned correspondingly on the respective chains and spaced apart a distance equal to the desired spacing between successive edges of the sign plates 2 as they pass the contact bank 7. As the chains 6 operate past the lower end of the magazine 1, the sign plates 2 are slid off of the bottom of the stack, one at a time, by lugs 19, thus effectively and positively selecting the successive sign plates and spacing them correctly on the chains.

The change of direction of the sign plates 2 between the magazine 1 and the contact bank 7 is accomplished by means of a specially constructed reel 20, and the reversal of the sign plates between the discharge side of the contact bank 7 and the top end of the magazine 1 is effected by a similarly constructed reel 21. These reels 20 and 21 consist of a pair of wheels rigidly affixed to rotating shafts 33 and spaced apart a distance equal to the spacing of the chains 6. Both of the side wheels of the reels 20 and 21 are provided around their peripheries with slots or notches 23 shaped to receive the lugs 19 provided on the chains and spaced apart a distance corresponding to the spacing of the lugs along the chains. Thus, as chains 6 operate around reels 20 and 21, lugs 19 engage with the respective notches 23 in the periphery of the reels, with the sign plates 2 confined in the chambers or compartments

bounded on one side by the reel, on the other side by the chains and at the respective ends by the lugs 19.

With the construction just described the sign plates 2 are handled through all changes in direction of their flow in such manner that each plate is under positive independent control at all times. This manner of handling the sign plates, particularly changing their direction of passage is a particularly important step in the operation of apparatus of this class. This arrangement eliminates the possibility or likelihood of jamming or stoppage of the plates in the reverse guide, and at other places, and avoids the confusion and disorder of flow which unavoidably occurs at times where the sign plates are pushed around a reversing bend or are dropped through a curved chute. The present invention provides for reliable, positive and independent handling of each sign plate throughout such changes in direction of flow as are necessary or desirable in the operation of the apparatus.

The handling of the sign plates 2 by means of the reels 20 and 21 makes it possible to handle the plates through changes in direction of flow in a minimum of space. This feature is apparent from Figure 1 of the drawing. The reels 20 and 21 need be only of sufficient size to enable the sign plates to be handled conveniently in the space between the chains and the reels. Since the dimension of the sign plates in the direction of the length of the chains is not great, the reels can be small, and practically the entire amount of space occupied in changing the direction of flow of the plates is determined by the diameter of the reels, only sufficient additional space being needed as is required to carry the return portion of the chain.

As the sign plates 2 are discharged from the reel 21 they are passed into the top of magazine 1. A guide member 24 is provided, as shown, at the top of the magazine to facilitate the deposit of the sign plates in the magazine proper side down. By way of precaution, the guide portion 24 is mounted through the medium of a movable section 25, so that if the magazine should become too full or if the plates should in any way not slide down into the magazine properly, the movable portion would be swung out, thus closing electrical contact 26 which is connected in circuit with a warning signal or with a relay to open the motor circuit (not shown).

The invention also contemplates an improved mechanical and electrical construction adapted for use in the contact bank 7. Referring to Figure 4, 27 indicates the insulating board in which the fixed contact posts 8 are mounted. The present improved construction comprises a fixed contact post consisting of an inner portion 28 and an

outer portion 29. The inner portion 28 lies inside of the insulating board 27 and is in engagement with the contact brush 9, as shown. The portion 29 of the fixed contact post has a shoulder 30 which fits against the outer side of the insulating board 27, as shown, and has a threaded projection 31 which extends through the insulating board 28 into threaded engagement with the contact portion 28. In the assembly of the contact bank portion 29, the fixed contact post is inserted through the tapped hole provided for that purpose in the insulating board 8 and the portion 28 is screwed on in the position shown and firmly tightened up. The contact brushes 9, together with the associated parts in which they are mounted, as shown, are then put in place. The construction and mounting of the contact brushes 9 is shown and described in detail in my above mentioned copending application. Lead wires 32 which connect the fixed contact posts with the lamps on the sign board are then merely inserted into the hole provided in the outer end of the portion 29 and may be secured therein by squeezing portion 29 together, as indicated at 33, by a suitable tool. By means of this construction the contact posts may be rapidly and readily assembled on insulating board 27, a rigid and reliable attachment of the contact posts to the board is effected and an extremely quick and convenient means for attaching the lead wires thereto is provided.

The invention is defined in the following claims in terms of those features of construction, combination and design, which give rise to the improvements and advantages attained by the present apparatus, all as illustrated and described herein. While the structural embodiments shown and described herein are present preferred embodiments, it is evident that changes may be made in the exact structure and arrangement of parts without departing from the scope of the invention as defined in the appended claims.

I claim:

1. Electric sign control apparatus of the class disclosed, which comprises sign plates, transporting means for engaging said plates to effect movement thereof, and means for effecting a change in the direction of movement of said plates which comprises a rotatable member adapted to engage said plates on the side thereof opposite the said transporting means, and means for causing the said transporting means to follow around the periphery of said rotatable member a distance sufficient to effect the desired change in direction, whereby the sign plates are positively held between the said transporting means and the said rotatable member and are thereby positively guided and supported throughout the desired change in the direction of movement.

2. Apparatus of the class described which comprises sign plates, a magazine for containing said plates, traveling chains upon which sign plates from said magazine are successively placed in proper sequence for presentation of the sign, a contact bank past which said sign plates are moved, a rotating reel interposed in the path of the said sign plates between the discharge side of the contact bank and the return opening of said magazine, and means for passing said chains about a portion of the periphery of said reel with the said sign plates held between said chains and said reel to thereby effect a change 10 in the direction of movement of the said plates.

3. Apparatus of the class described which comprises sign plates, a magazine for containing said plates, traveling chains upon which sign plates from said magazine are successively placed in proper sequence for presentation of the sign, spacing elements provided on said chains to contact with the sign plates and carry the said respective plates in proper spaced relation on said chains, a contact bank past which said sign plates are moved, a rotating reel interposed in the path of the sign plates for effecting change in direction of movement thereof, and means for passing said chains about a portion of the periphery of said reel with the sign plates held between said plates and said reel, to thereby effect a change in direction of movement of said plates and at the same time preserving the proper sequence and proper space relation of said plates.

4. Apparatus of the class described which comprises sign plates, a magazine for containing said plates, traveling chains upon which sign plates from said magazine are successively placed in proper sequence for presentation of the sign, spacing elements provided on said chains for engaging with the sign plates and carrying them in properly spaced relation on the chains, a contact bank for acting electrically upon said sign plates, a rotating reel interposed in the path of said sign plates between the discharge side of the magazine and the intake side of the contact bank, means for passing said chains about a portion of the periphery of said reel with the sign plates held between the chains and the reel to thereby redirect the movement of the sign plates into proper direction for introduction into the contact bank, a second rotating reel interposed in the path of movement of said sign plates between the discharge side of the contact bank and the intake side of said magazine, and means for passing said chains about a portion of the periphery of said reel with the sign plates held between the chains and the reel to thereby effect reversal of the plates into proper position for reentry into said magazine.

5. Apparatus of the class described which

comprises sign plates, traveling chains for carrying said sign plates in proper sequence for presentation of the sign, spaced lugs provided on said chain, a rotatable reel located along the path of travel of said sign plates, means for passing said chains over a portion of the periphery of said reel with the said sign plates held between the chains and the reel, and means provided on said reel for engagement with said spaced lugs on the chains to thereby effect a positive engagement between the chains and the reel with resultant synchronous movement thereof.

6. Apparatus of the class described which comprises sign plates, traveling chains for transporting said sign plates in proper sequence, spacing elements provided on said chains for engagement with the rear edges of said sign plates to thereby effect proper spacing of said plates on the chains, a rotatable reel located along the path of movement of said chains and sign plates, means for passing the chains around a portion of the periphery of said reel, means provided on said reel for engagement with said spacing elements on the chain to hold the chains a short distance off of the periphery of the reel and thus form a series of compartments for carrying the said sign plates, said compartments being formed between the periphery of the reel, the traveling chains, and the spacing elements at the front and rear of each plate.

7. In an apparatus of the class disclosed, sign plates, chains upon which said sign plates are successively laid, spacing elements for effecting and maintaining proper spacing of the sign plates upon said chains, and a direction changing means which comprises a rotatable reel around which said chains are passed with said spacing elements adjacent the reel to thereby positively hold and carry the sign plates between the chains and the reel, while proper spacing of said plates is maintained.

8. Apparatus of the character disclosed comprising in combination sign plates, an upright magazine for supporting a body of the sign plates superposed on top of each other in a substantially vertical stack, said sign plates having runners along the edges of the same serving as supporting members for the plates and sign elements on the plates between said runners and of less height than said runners, a contact bank for actuation by the sign elements of the plates, chains extending beneath the foot of the magazine and having upstanding lugs engageable with the sign plates to extract them one at a time from the foot of the stack, said chains being guided to carry the sign plates past the contact bank, a rotating reel overstanding the upper end of the magazine, said chains extending over and about said reel and confining the sign plates to the reel and whereby

said plates are reversed and deposited in reversed order on top of the stack.

9. Control mechanism for talking signs comprising in combination a contact bank, sign plates for operating said contact bank, a magazine for supporting a stack of the sign plates in superposed order a sign plate reversing reel at the head of and overstanding the top of the magazine and chains operating beneath the foot of the magazine, past the contact bank and about the reversing reel whereby to extract the sign plates from the bottom of the stack, carry them past the contact bank and deposit them in reversed order on the top of the stack.

In testimony whereof I affix my signature.
FRANCIS E. J. WILDE.
